[57] CLAIM

The ornamental design for a combined lamp and table,
as shown and described.

DESCRIPTION

FIG. 1 is a top, side perspective view of a combined lamp and table showing my new design;FIG. 2 is a side elevational view thereof, all sides being identical; and,FIG. 3 is a top plan view of a second embodiment of my new design.The first and second embodiments are identical except for the shape of the table. The interior light bulbs are shown in broken lines in FIG. 3 for illustrative purposes only.FIG. 1

FIG. 3

UNITED STATES PATENT AND TRADEMARK OFFICE
CERTIFICATE OF CORRECTION

PATENT NO. : Des. 330,943

Page 1 of 4

DATED : November 10, 1992

INVENTOR(S) : Helmut H. Masch

It is certified that error appears in the above-identified patent and that said Letters Patent is hereby corrected as shown below:

The title page, should be deleted to be replaced with the attached title page.

The drawing sheet consisting of Figs. 1 - 2 should be deleted to be replaced with the drawing sheet, consisting of Fig. 1, as shown on the attached page.

The drawing sheet consisting of Fig. 3, should be deleted to be replaced with the drawing sheet consisting of Figs. 2 - 3, as shown on the attached page.

Signed and Sealed this

Ninth Day of November, 1993

Attest:

BRUCE LEHMAN
